UNITED STATES PATENT OFFICE.

ALFRED MOLANDER, OF SAULT STE. MARIE, ONTARIO, CANADA.

MECHANICAL MINERAL-CONCENTRATOR.

1,235,497.

Specification of Letters Patent.

Patented July 31, 1917.

Application filed October 19, 1914. Serial No. 867,385.

To all whom it may concern:

Be it known that I, ALFRED MOLANDER, of the city of Sault Ste. Marie, in the District of Algoma, in the Province of Ontario, Canada, have invented certain new and useful Improvements in Mechanical Mineral-Concentrators, of which the following is the specification.

My invention relates to improvements in mechanical mineral concentrators and the object of the invention is to devise a machine of this class which will have a maximum capacity and by which all metal values of the size which have hitherto been extracted from the ore are prevented from floating and passing off with the waste matter through the overflow outlet and it consists essentially of a main receptacle having a longitudinally slotted outlet at the bottom, a water inlet in proximity to the top and at each side of the main receptacle, a central discharge trough located slightly below the water level and leading to a discharge outlet at the end of the main receptacle and a feed slot located at each side of the main receptacle and entering the receptacle below the level of the water contained in such receptacle, means for feeding the crushed ore in a thin stream thereto, means for agitating the water contained in the receptacle, means for regulating the amount of agitation and means for separating the precipitated values from the liquid as they pass off through the outlet slot of the main receptacle as herein-after more particularly explained by the following specification.

Figure 1, is a side elevation of my machine.

Fig. 2, is a longitudinal section on line $x-y$ Fig. 3 showing the major portion of the driving mechanism removed and showing the rubber covered roller in full.

Fig. 3, is a cross section through Fig. 2.

Fig. 4, is a plan view of my machine showing the major portion of the driving mechanism removed.

Fig. 5, is a plan sectional detail on line $x'-y'$ Fig. 3.

In the drawings like letters of reference indicate corresponding parts in each figure.

1 is the main receptacle, the bottom 2 of which is inclined downward from each side of the receptacle toward the center and is provided at the center with a longitudinally extending exit slot 3. 4 and 5 are a series of longitudinal slots formed in the top of

the receptacle 1. 6 and 7 are feed slots formed in the sides of the receptacle 1 in proximity to the bottom of such sides. 8 and 9 are receptacles extending longitudinally at each side of the main receptacle 1. The receptacles 8 and 9 are each provided with feed hoppers 10 and 11 designed to feed the crushed ore through the slotted openings 12 and 13 into the receptacles 8 and 9. The receptacles 8 and 9 are supported from the side of the main receptacle 1 by brackets 14 and 15. 16 and 17 are exit slots formed in the lower inner corner of the receptacles 8 and 9. 19 and 20 are inclined chutes extending respectively from the exit slots 16 and 17 to the feed slots 6 and 7 leading into the main receptacle 1. 21 and 22 are screw conveyers each mounted on a shaft 23 suitably journaled in the ends of the receptacles 8 and 9. 24 and 25 are ribs extending longitudinally of the receptacles 8 and 9 respectively along the outer edge of the slotted outlets 16 and 17. By this means when the screw conveyers 21 and 22 are revolved they gradually feed the crushed ore over the upper edge of each of the ribs 24 and 25 so that the ore passes in a thin stream through the openings 16 and 17. 26 is a copper pan fitting the bottom of the main receptacle 1 and provided with slots 27 and 28 in the side walls thereof so as to be opposite the feed slots 6 and 7.

29 and 30 are water supply pipes leading through one end of the main receptacle 1 and extending longitudinally thereof in proximity to each side and near the top of such receptacle. The pipes 29 and 30 are provided with perforations 31 (see Fig. 2) of a suitable size through which the water passes into the main receptacle. 32 is a dotted line indicating the water-level in the main receptacle 1 (see Fig. 3). 33 is a trough extending longitudinally through the center of the main receptacle 1 slightly below the level of the water indicated by the dotted line 32 as contained in the main receptacle 1. The trough 33 leads into the outlet waste pipe 34. 35 is a screen supporting frame comprising a pair of upper longitudinal members 36 and 37, a pair of lower longitudinal members 38 and 39, cross connecting members 40 and 41 connecting the upper longitudinal members 36 and 37 together at their ends, cross connecting members 42 and 43 connecting the lower longitudinal members 38 and 39 together at their

ends, cross connecting members 44 and 45 connecting respectively the upper longitudinal members 36 and 37 and lower longitudinal members 38 and 39 together intermediate 5 of their length, a series of vertical bars 46 connecting the longitudinal members 38 and 36 together and a similar series of bars 47 connecting the longitudinal members 39 and 37 together.

10 48 are a series of screens formed of suitable fine wire mesh through which the longitudinal members 36, 37, 38 and 39 extend. The screens 48 are separated apart by suitable spacing pieces 49 carried by all of the longitudinal bars 38 and 39. By this means the screens 48 are held in a parallel vertical position within the receptacle. The lower edges of the screens 48 are V-shaped in form so as to substantially follow the contour of the 15 lower portion of the receptacle, such lower edge being provided with suitable copper binding 50. 51 and 52 are two series of hangers connected at their lower ends to the longitudinal bars 36 and 37 and extending 20 at their upper ends through the slots 4 and 5 respectively, such upper ends being provided with right angular extensions 53 and 54. 55 and 56 are two series of plates provided with longitudinal ball ways 57 in which the 25 ball bearings 59 (see Fig. 3) are supported. The extensions 53 and 54 are provided with concaved recesses bearing on top of the ball bearings 59. By this means the screen frame 35 and screens 48 supported thereby are 30 capable of being reciprocated bodily to a limited extent within the main receptacle 1.

35 60 is the main shaft (see Fig. 1) supported in a suitable bearing 61 carried by the top of the main receptacle 1. 62 is a main 40 standard frame. 63 is a shaft journaled in the standard frame 62. 64 is a face friction gear mounted upon the shaft 63. The upper end of the standard frame 62 is provided with a bearing 65 in which the end of the 45 main shaft 60 is journaled. 66 is a sprocket wheel carried on the outer end of the main shaft 60. 67 is a sprocket wheel carried on the outer end of the shaft 63 and 68 is a sprocket chain forming a driving connection 50 between the sprocket gears 66 and 67. 69 is a shaft journaled in brackets 70 extending from the standard frame 62.

71 and 72 are eccentrics secured upon the shaft 69 and 73 and 74 are eccentric straps 55 each provided with a forked end 75. 76 is a block carried by each of the longitudinal members 36 and 37. 77 is a bar extending outwardly from each block 76 to which it is secured. The bars 77 extend through openings 78 formed in the end wall of the main receptacle 1. The outer end of each bar 77 is pivotally connected in the forked end 75 of the corresponding eccentric strap 73 or 80 74. The shaft 69 is provided with a longitudinal feather key 79. 80 is a friction gear

slidably mounted upon the shaft 69 and in contact with the face of the face friction gear 64. The hub 81 of the friction gear 80 is provided with an annular groove 82. 83 is a threaded spindle journaled in the outer end of the bracket 70 and held from longitudinal movement by the annular shoulders 84. 85 is a turning knob fastened upon the outer end of the threaded spindle. 86 is a sleeve having an internal thread engaging 75 with the thread of the spindle 83. The sleeve 86 is provided with an arm 88, the end of which extends into the annular groove 82. By this means the friction gear 80 may be adjusted radially in relation to the center of the face friction gear 64. 89 are supports for the main receptacle 1. 90 and 91 are bearing frames similar in construction. Each of the bearing frames 90 and 91 is provided with lugs 92 and 93 through which 85 extend suitable bolts to connect the same to the bottom of the main receptacle. Each bearing frame 90 and 91 is provided with a surrounding rib 94 extending from the inner face thereof and cross rib 95. Each frame 90 and 91 is provided with an open portion 96 (see Fig. 2). 97 and 98 are bearing plates slidably held in the frame formed by the ribs 94 and 95. Each plate 97 and 98 is provided with a bearing portion 99 (see 95 Fig. 2) having a central orifice 100 provided with an enlargement 101 at its inner end. 102 and 103 are shafts journaled in the orifices 100 of the plates 97 and 98. One of the shafts 102 or 103 is extended outwardly 100 as indicated particularly in Fig. 2 so as to be connected to a suitable driving source.

104 are rollers secured on the shafts 102 and 103. Each of the rollers 104 is provided with a rubber covering 105 which revolve in contact. 106 and 107 are metallic rollers revolving in contact with the rubber covering 105 of the rollers 104. As indicated by dotted lines in Fig. 2 the ends of the rollers 106 and 107 are provided with reduced ends 108. Between the plates 97 at each end of the machine extends a metallic bar 109 provided with a concaved lower portion 110 in which the periphery of the roller 106 fits. 111 is a bar secured to the lower face of the main receptacle 1 and is provided with a ground lower face engaging with the upper ground face of the bar 109. The plate 98 is provided with a vertical groove 112 and the plate 97 with a vertical tongue 113 fitting within the vertical groove 112 so as to form a water tight joint. 114 and 115 are bars similar to the bars 109 and 111, the bars 114 and 115 being located on the opposite side of the slotted opening 3 to the bars 109 and 111. The bars 114, 115, 109 and 111 co-act with the rollers 106 and 107 to form a water tight wall between the bottom of the receptacle 1 and the rubber cover 105 of the revolving 130

rollers 104, 116' are adjusting screws by which the bearing plates 97 and 98 may be adjusted to and from each other.

Having described the principal parts involved in my invention I will briefly describe the operation of the same.

The ground ore is fed into the hoppers 10 and 11 and passes through the slots 12 and 13 into the receptacles 8 and 9. The revolving conveyers 21 and 22 gradually distribute the material longitudinally of the receptacles 8 and 9 and gradually spill it in a thin stream over the upper edge of the ribs 24 and 25. These streams of ore particles pass down the chutes 19 and 20 into the main receptacle beneath the liquid level.

It is a well known fact that ore particles when fed into the liquid from above the liquid level are mixed with air and the air intermixed therein causes the metallic particles to rise to the surface, and therefore, prevents proper precipitation.

By my device as above described the ore is fed into the main receptacle below the liquid level and, therefore, the danger of air mixing with the particles is obviated. The screens 48 are agitated by the revolving eccentrics 71 and 72, agitating the liquid in the receptacle, which agitation causes the lighter or rock particles to rise to the surface of the liquid in the main receptacle and the heavier or metallic particles to be precipitated to the bottom of such receptacle. In order to do this the screens have to be vibrated at a speed in proportion to the size of the ore particles. This rate of speed has to be found by experience. In order to adjust the mechanism to vibrate the screens at the speed required to precipitate the particles of the size which have been fed into the machine I turn the knob 85 and threaded spindle 83 so as to move the sleeve 86 longitudinally thereon. By means of the arm 88 engaging the annular groove 82 I move the friction gear 80 radially in relation to the face friction gear 64. By this means the screen driving mechanism is regulated in order to reciprocate the screens at the desired speed. The waste or rock material, rising to the surface of the liquid contained in the main receptacle 1, floats gradually on the surface to the center of the receptacle 1 and over each side edge of the trough 33 and then out through the waste outlet 34. The normal level of the liquid is maintained by the supply fed in through the perforations of the pipes 29 and 30. The precipitates or concentrates pass downwardly through the slot 3 with a certain amount of the liquid, such liquid passing off through the waste pipes 116 and 117.

It will, of course, be understood that the rollers 104 are revolving continually in con-

tact and that the precipitates are caught between the revolving surfaces of the rollers and fed downwardly between such rollers into a suitable receptacle.

From this description it will be seen that I have devised a very simple machine which will extract from ore all metal values such as are commonly extracted from ore. In certain classes of minerals such as sulfids, however, the ore after having passed through pulverizing rollers is broken up into such very fine particles as to escape observation even through a magnifying glass and mining men as a rule have been unaware as to their existence and those particles have, therefore, been wasted. These particles when subjected to the operation of my machine rise to the surface of the liquid and are collected in the foam lying on the surface of the liquid which gradually gathers in the inlet passage. Such foam can be scooped out from beneath the inlet from time to time. These very fine particles form themselves into a substance in the feed inlet by a natural attraction or affinity existing between the particles of metal of the same kind which cements them together.

It will thus be seen that my machine by this operation enables the operator to remove from the ore a very much higher percentage of the metal contained therein than is possible by any other method.

What I claim as my invention is:

1. In a mineral concentrator, a precipitating receptacle, liquid supply ducts designed to maintain the liquid within the receptacle at the required level, means for feeding crushed ore into the receptacle beneath the water level, a waste discharge located slightly beneath the liquid level, and a series of vertical parallelly arranged screens, a suitable frame connecting the screens together, means for slidably supporting the screen frame within the receptacle, and means for imparting a reciprocating movement to the frame, as and for the purpose specified.

2. In a mineral concentrator, a precipitating receptacle, liquid supply ducts designed to maintain the liquid within the receptacle at the required level, means for feeding crushed ore into the receptacle beneath the water level, a waste discharge located slightly beneath the liquid level, a series of vertical parallelly arranged screens, a suitable frame connecting the screens together, means for slidably supporting the screen frame within the receptacle, means for imparting a reciprocating movement to the frame, and means for controlling the speed of the reciprocating movement, as and for the purpose specified.

3. In a mineral concentrator, a precipitating receptacle designed to contain a body of water, of means for feeding pulverized

ore into the body of water below the surface thereof, substantially vertical means for causing uniform vibrations in the water substantially without water flow comprising a plurality of reciprocating screens, the distance between the screens being less than the length of their movement.

4. In a mineral concentrator, a precipitating receptacle designed to contain a body of water, means for feeding crushed ore into the receptacle intermediate of the height of the body of water, a reciprocating frame substantially of the same cross sectional area as the body of water and carrying a parallel series of members each provided with cross parallel substantially vertical members forming narrow horizontal openings therebetween arranged in close proximity one above the other, and means for reciprocating the frame to produce vibrations in the water.

5. In a mineral concentrator, a precipitating receptacle designed to contain a body of water, of means for feeding pulverized ore into the body of water below the surface thereof, substantially vertical means for causing uniform vibrations in the water substantially without water flow whereby

an upward ore particle impelling pressure is produced, and means for varying said upward pressure.

6. In a mineral concentrator, a stationary receptacle containing a deep body of water and having a suitable outlet through which the surface water flows, means for feeding crushed ore into the receptacle beneath the water level, a horizontally vibrated series of parallelly arranged vertical screens, and means for vibrating the screens beneath the surface of the water whereby the rock particles are carried upward to the outflowing surface water.

7. In a mineral concentrator, a stationary receptacle containing a deep body of water, means for feeding crushed ore into the receptacle beneath the water level and a series of vertical parallelly arranged screens supported in the receptacle beneath the water level and in close proximity one to the other, and means for vibrating the screens in a horizontal direction.

ALFRED MOLANDER.
